SHOE SOLE

George H. Bingham, Jr., Westminster, and Otto Y. Olson, Taneytown, Md., assignors to Cambridge Rubber Company, Cambridge, Mass., a corporation of Maryland

Original design application Dec. 14, 1962, Ser. No. 72,860, now Patent No. Des. 196,559, dated Oct. 15, 1963. Divided and this application May 29, 1963, Ser. No. 75,414

Term of patent 14 years

(Cl. D7—5)

FIGURE 1 is a side elevational view of a shoe sole embodying my new design; the broken line showing of the shoe upper being for purposes of illustration only.

FIGURE 2 is a bottom plan view of the shoe sole embodying my new design;

FIGURE 3 is a vertical transverse sectional view, as seen on the line 3—3 of FIGURE 2;

FIGURE 4 is a vertical longitudinal sectional view, as seen on the line 4—4 of FIGURE 2.

This is a division of application Serial No. D.72,860, filed December 14, 1962, and now Patent No. Des. 196,559.

We claim:

The ornamental design for a shoe sole, as shown and described.
